To all whom it may concern:

Be it known that I, EDWARD L. This gem is provided with a plurality of distinct and individual portions raised from the face of a single gem body to present the

appearance of a cluster of separate gems when mounted in a setting.

Figure 1 is a top view, Figure 2 is a side elevation, Figure 3 is a sectional elevation on line 3—3 of Figure 1, and Figure 4 is a perspective view of a gem, illustrating my new design.

I claim:

The ornamental design for a gem, substantially as shown and described.

EDWARD L. WEED.
